UNITED STATES PATENT OFFICE

BRIAN A. LAPIN, OF PHILADELPHIA, PENNSYLVANIA, ASSIGNOR TO PROCTOR & SCHWARTZ ELECTRIC COMPANY, OF PHILADELPHIA, PENNSYLVANIA, A CORPORATION OF PENNSYLVANIA

DESIGN FOR A TOASTER

Application filed January 18, 1930. Serial No. 34,180. Term of patent 14 years.

To all whom it may concern:

Be it known that I, BRIAN A. LAPIN, a citizen of the United States, residing in Philadelphia, Pennsylvania, have invented a new, original, and ornamental Design for a Toaster, of which the following is a specification, reference being had to the accom-

panying drawing, in which the figure is a perspective view of the toaster, showing my new design.

I claim:

An ornamental design for a toaster, substantially as shown.

BRIAN A. LAPIN.
